UNITED STATES PATENT OFFICE.

ARSENE HEBERT, OF MANCHESTER, NEW HAMPSHIRE, ASSIGNOR TO GEORGE J. P. FRECHETTE, OF SAME PLACE.

LASTING-HAMMER.

SPECIFICATION forming part of Letters Patent No. 620,650, dated March 7, 1899.

Application filed December 3, 1897. Serial No. 660,594. (No model.)

To all whom it may concern:

Be it known that I, ARSENE HEBERT, a citizen of Great Britain, residing at Manchester, in the county of Hillsborough and State of New Hampshire, have invented certain new and useful Improvements in Lasting-Hammers; and I do hereby declare the following to be a full, clear, and exact description of the invention, such as will enable others skilled in the art to which it appertains to make and use the same.

This invention relates to that class of pliers which are used by shoe-lasters and which contain a magazine or reservoir for tacks, the object being to render it unnecessary for the operator to carry tacks in his mouth and to combine with the tool a mechanism which carries the tacks into the hammer, whereby they are driven into the work one at a time whenever the operator brings the hammer down as in the act of driving a tack. This I accomplish by making the hammer movable away from and toward the pliers, the first movement causing a tack to drop into said hammer and the second to drive the same where desired, as fully set forth in the following specification and claims and clearly illustrated in the accompanying drawings, forming a part of the same, of which—

Figure 1 is an elevation of my improved pliers, Fig. 2 being a plan view of the same. Fig. 3 is a longitudinal section of that portion of my improved pliers carrying the movable hammer, the tack-magazine, the raceway, and my improved devices for depositing the tacks at the bottom of the hammer and sticking the same into the work. Fig. 4 is a cross-section of the tack-magazine and that portion of the pliers to which it is attached. Fig. 5 is a broken elevation showing my improved hammer and a portion of the projection to which it is attached. Fig. 6 is a broken plan showing a portion of the pliers with the raceway, the magazine in section, and a sliding stop-plate for letting the tacks one at a time into the hammer.

Similar reference-letters denote like parts throughout the various views.

The pliers are of novel construction, A being the stationary member, having a jaw *a*, and *B* the movable member, to be grasped by

the hand of an operator. A movable jaw *b* is pivoted to the stationary member forward of its jaw, and the parts *B b* are connected, respectively, at *b' b'* by a bar *C*. 55

A tack-magazine is secured to the part *A* forward of the jaws *a b* and consists of a shell *D*, having an opening at its top, as at *d*, and provided with a swiveled cover *d'*.

Within the magazine *D* is a tack-raceway 60 consisting of a pair of plates *E*, placed vertically side by side, with sufficient space between them to receive the tacks, the heads of which rest upon the curved top of said plates, and flaring extensions *e e* are formed upon the upper edge of and at one end of said plates, each of said extensions reaching to the adjacent side of the magazine *D* for a portion of its length, as shown best in Figs. 3 and 4. The movement of the pliers up and down in 70 the hand of an operator throws the tacks upon said extensions and deposits them in the raceway, whence they pass down and into an opening *a'* in the part *A* for delivery to the hammer. A groove *a²* is formed in the part *A*, 75 terminating in said opening *a'*, and the plates *E* are secured at opposite sides of said groove by screws passing through their flanges *e' e'*, as shown. The opening or tack-passage *a'* is formed in a cylindrical projection *a³*, provided with an annular recess *a⁴* and a plunger *a⁵*. The recess *a⁴* contains a helical spring *F*, and the movable hammer *G* has an internal annular shell *g*, which enters said recess *a⁴* and bears against the spring *F*, as in Fig. 3, 85 and said hammer is allowed a limited movement upon said projection *a³* by means of a screw *H*, passing through an elongated opening *g'* and threaded to said projection *a³*.

The central opening in the hammer *G* is reduced at its bottom to about the size of the head of a tack, the plunger *a⁵* being of proper size to pass into the reduced opening *g'* of the hammer, when the latter is caused to rise upon the projection *a³* and drive a tack. In order 95 to deliver one tack only to said hammer at each movement of the same, I provide a suitable stop device at the top and bottom, that at the top consisting of a sliding plate *I*, fitting a recess in the part *A* and held normally, 100 as shown in Fig. 6, by means of the spring *J* and adapted to be moved against the pressure

of said spring by a suitable rocker K, pivotally attached to the part A, as in Figs. 1 and 2, and actuated by the upward movement of the hammer G, which throws the lower end 5 of the rocker K out and moves the plate I so that its slot *i* will register with the raceway E to receive a tack; the downward movement of the hammer permitting the plate I to again assume the position shown in Fig. 6.

10 The stop at the lower end of the hammer consists of a slide L, having its inner end beveled on top, as at *l*, and held so as to normally cover the reduced portion of the tack-outlet in the hammer by a suitable spring M, 15 and when a tack X is let in at the top it drops down against this slide and under the plunger *a*⁵, as in Fig. 3, the upward movement of the hammer upon the projection *a*³ bringing the plunger *a*⁵ in contact with the tack X and 20 the beveled portion *l* of said slide L, moving the latter out of the way while the tack is driven into the work.

25 A curved plate N is placed over the raceway E to prevent the tacks from jumping out and serving to hold the stop I in proper place and is secured in position by screws *n*.

30 It is also desirable to prevent tacks which have passed down the raceway from again returning to the magazine D, and this I accomplish by means of a little rocker or bell-crank *n'*, as shown in Fig. 1.

35 The movable hammer G is held in its elevated position by a suitable spring-actuated lever O, provided with a projection *o*, which engages the under edge of a flange formed at the top of said hammer, said lever being pivotally attached at *p* to the part A, and a suitable spring P holds the lever in contact with the hammer when elevated, the lower end of

the lever being adapted to be released from 40 the flange of said hammer by a finger of an operator.

Having described my improvements, what I claim is—

1. The combination with a handle and relatively-fixed member, of a hollow cylindrical projection extending from the member, a spring-actuated hollow hammer telescoping upon the projection, means for delivering tacks to the hammer, and mechanism for automatically retaining the hammer in its elevated position against the resistance of its spring, substantially as specified.

2. The combination with a handle and relatively-fixed member, of a hollow cylindrical projection extending from the member, a magazine carried by the member, means for conveying tacks from the magazine to the interior of the projection, a hollow hammer telescoping with the cylindrical projection and spring-actuated in one direction, a tack-retaining stop at the lower end of the hollow hammer, a sliding plate located intermediate of the member and magazine and designed to regulate the feed of the tacks, a rocker operatively connected with said plate and designed to be actuated by the movable hammer, and a spring-actuated latch-lever designed to engage the hammer and to retain it in its elevated position, substantially as specified.

65 In testimony whereof I affix my signature in presence of two witnesses.

ARSENE HEBERT.
